UNITED STATES PATENT OFFICE.

JOHN B. THELEN AND PETER L. BOULICAULT, OF MILWAUKEE, WISCONSIN.

SAFETY DEVICE FOR AEROPLANES.

Application filed September 26, 1925. Serial No. 58,803.

To all whom it may concern:

Be it known that we, JOHN B. THELEN and PETER L. BOULICAULT, both citizens of the United States, and residents of Milwaukee, in the county of Milwaukee and State of Wisconsin, have invented certain new and useful Improvements in Safety Devices for Aeroplanes; and we do hereby declare that the following is a full, clear, and exact description thereof.

This invention relates to safety devices for aeroplanes.

Objects of this invention are to provide a device which may be attached to a aeroplane and which will provide means for protecting the aeroplane against damage in case of falling.

More specifically, this invention is designed to provide means which act to restrain the motion of the aeroplane during a fall and cause it to descend at a rate which will not injure it or its occupant upon landing, in case the aeroplane becomes disabled from any cause.

Further objects are to provide a safety device for aeroplanes which may be instantly brought into use in a very simple manner, which is automatic in its unfolding operation, and which, when not in use, may be bodily carried by the aeroplane.

Further objects are to provide a safety device for aeroplanes which may be adjusted to occupy a small amount of space when the aeroplane is upon the ground to facilitate storing of the machine.

An embodiment of the invention is shown in the accompanying drawings, in which:

Figure 1 is a side elevation of the aeroplane with the device in position thereon.

Figure 2 is a sectional view on the line 2-2 of Figure 1.

Figure 3 is a fragmentary detail section of the rear end of one of the tubes, such view showing the parachute attachment folded in position in full lines and in extended position in dotted lines.

Figure 4 is a sectional view on the line 4-4 of Figure 3.

Referring to the drawings, it will be seen that the device is carried by means of a central standard 1 secured within the body portion 2 of the aeroplane. This central standard extends upwardly and carries a longitudinally extending shaft 3, as shown in Fig-

2. This shaft is preferably reenforced by 55 means of standards 4 and 5, as shown in Figure 1, in order to increase the stiffness of the structure.

The standard 1 continues upwardly and carries a tube 6. A pair of side tubes 7 and 8, similar to the tube 6, are provided and are carried by arms 9 and 10 pivoted to the shaft 3, as shown most clearly in Figure 2. These arms are joined to a crosshead 11 by means of links 12. The standard 1 is provided with a plurality of apertures 13 adapted to receive a bolt or similar fastening member 14 carried by the crosshead 11 when it is desired to lock the parts in a fixed position. The crosshead is adapted to be moved by 70 means of the cam 15, such cam being pivoted to the standard 1 and provided with a manipulating handle 16. Thus when the machine is on the ground and it is desired to elevate the tubes 7 and 8, it is merely necessary to remove the bolt 14 and rock the cam by means of the lever 16. However, in order to hold the arms 9 and 10 against upward motion, a pair of cables 17 and 18 are provided whose upper ends are attached to 75 such arms and whose lower ends are attached to a drum operated by means of a crank 19.

The drum is equipped with ratchet teeth 20 which are temporarily locked by means of 85 the pawl 21. Each of the tubes 6, 7 and 8 is constructed of light metal, such for instance, as aluminum, and is open at its front and rear end. Consider for example Figure 90 4 in which one of the tubes is shown in considerable detail, for instance tube 6, it being understood that all of the tubes and their associated parts are of similar construction.

The tube is provided with an annular housing 22 whose rear portion is spaced from the inner surface of the tube, as shown in Figure 2. A parachute formed of any suitable flexible material such as canvas, silk, or any suitable material, is indicated by the reference character 23 and, as will be noted 100 from Figure 4, has its edges attached to the rear edge of the tube, as shown at 24. This parachute is in the nature of a bag and is normally folded upon itself, as shown in full lines in Figure 3, with the fold beneath the 105 annular housing 22 within the tube. The outer end of the parachute carries a spider 25 which is shown in greater detail in Fig-

ure 4. This spider offers very little resistance to the air and allows it to flow freely therethrough under normal conditions. It is provided with a central apertured hub 26 which 5 slidably carries a pin 27. This pin has, at its forward end, a pivotal connection with a disk or plate 28, such plate normally occupying the position shown in full lines in Figure 3.

10 A control cable 29 extends to the plate 28 and passes over pulleys 30 and 31 (see Figures 1 and 3) and extends downwardly to the cock pit of the aeroplane. If desired, all of the cables may be joined or else a single 15 cable may be run from each of the plates 28.

When the aeroplane makes its flight, the tubes are in the position shown in Figure 2 and remain in this position, under normal conditions except during storing of the machine. If for any reason the aeroplane should fall, it is merely necessary for the operator to pull upon the cables 29. This action causes the disks 28 to pivot about the forward ends of the pins 27. The air rushing through the tubes will force the plate rearwardly into contact with the spider, the pin 27 freely sliding through the hub 26. This closes the parachute and the wind pressure forces it out rearwardly from the tube, as shown in dotted lines in Figure 3. The three parachutes, therefore, retard the motion of the aeroplane and cause it to descend at a rate which will not injure either the aeroplane or the occupants therein.

35 It will be seen that an extremely simple type of safety appliance for aeroplanes has been provided which will effectively control the descent of an aeroplane, and which may be very quickly thrown into operation as the case demands.

It will be seen further that the safety appliance may be readily adjusted and controlled from the cock pit of the aeroplane.

Although the invention has been described in considerable detail, it is to be understood that the invention may be variously embodied and is, therefore, to be limited only as claimed.

We claim:

50 1. The combination of an aeroplane, a frame extending therefrom, a safety appliance carried by said frame and consisting of a tube open at both ends to normally permit the passage of air therethrough, a parachute normally folded within said tube, and means

to render said passage of air effective to project the parachute from the tube.

2. A safety appliance for aeroplanes comprising a frame adapted for attachment to the body of the aeroplane, a plurality of tubes carried by said frame and extending longitudinally of the body of the aeroplane, said tubes being open at their front and rear ends to permit passage of air therethrough, a plurality of parachutes carried by said tubes and normally folded within said tubes, said parachutes having open ends, and means for closing one of the open ends of said parachutes, whereby they will be forced rearwardly from said tubes into their expanded position by the passage of air through said tubes.

3. A safety appliance for aeroplanes comprising a frame adapted for attachment to the body of the aeroplane, a plurality of tubes carried by said frame and extending longitudinally of the body of the aeroplane, said tubes being open at their front and rear ends, to permit passage of air therethrough, a plurality of parachutes carried by said tubes and normally folded within said tubes, said parachutes having open ends, and means for closing one of the open ends of said parachutes, whereby they will be forced rearwardly from said tubes into their expanded position, and means for adjusting the relative position of said tubes.

4. The combination of an aeroplane having wings and a body portion, a frame secured to said body portion and projecting upwardly, a plurality of tubes carried by said frame and mounted above the wings of said aeroplane, said tubes having open front and rear ends, and each having an annular housing therein, a parachute attached to the rear end of each of said tubes and normally folded within the corresponding tube and positioned beneath said housing, said parachutes each having an open spider at its rear end, a pivotally and slidably mounted disk carried by each of said spiders, and means extending from said disks to the aeroplane for causing said disks to close the opening through said spider.

In testimony that we claim the foregoing 105 we have hereunto set our hands at Milwaukee, in the county of Milwaukee and State of Wisconsin.

JOHN B. THELEN.
PETER L. BOULICAULT.
